Primary Examiner — Angela J Lee(74) *Attorney, Agent, or Firm* — Banner & Witcoff, Ltd.(57) **CLAIM**

The ornamental design for a recording medium, as shown and described.

DESCRIPTION

FIG. 1 is a front, bottom and left side perspective view of a recording medium, showing our new design;
 FIG. 2 is a rear, bottom and right side perspective view thereof;

FIG. 3 is a front view thereof, the rear being symmetrical;
 FIG. 4 is a top view thereof, the bottom being identical;
 FIG. 5 is a left side view thereof;
 FIG. 6 is a right side view thereof; and,
 FIG. 7 is a cross sectional view thereof, taken along line 7-7 in FIG. 3.

The broken lines shown in FIG. 7 are for environmental purposes only and form no part of the claimed design.
